UNITED STATES PATENT OFFICE.

ADRIAAN NAGELVOORT, OF NEW YORK, N. Y., ASSIGNOR, BY MESNE ASSIGNMENTS, TO
VIRGINIA HALOID COMPANY, OF WILMINGTON, DELAWARE.

PROCESS OF SEPARATING SOLIDS OF DIFFERENT SPECIFIC GRAVITIES.

1,244,885.

Specification of Letters Patent. Patented Oct. 30, 1917.

No Drawing.

Application filed September 1, 1916. Serial No. 118,013.

To all whom it may concern:

Be it known that I, ADRIAAN NAGELVOORT, a citizen of the United States, residing at New York, county of New York, and State 5 of New York, have invented a new and useful Improvement in Processes of Separating Solids of Different Specific Gravities, of which the following is a full, clear, and exact description.

10 In the gravity separation of solids by means of a liquid, a certain amount of the liquid is carried off with the separated constituents. The separating liquid is usually too valuable to be lost and an economical 15 execution of the process necessitates the recovery of the liquid as carried off by the solids so that it may be returned to the separating tank for re-use.

20 In an application filed by me on the 16th of June, 1916, Serial No. 103,937, I have described a process which I have applied to the separation of pure iron ore from silicious gangue, in which I employ, as a liquid separant, tin bromid or arsenious bromid, or a 25 mixture of the two, or some other suitable separant, and subject the separated solids, after their emergence from the separating tank, to a washing action in liquid carbon bisulfid or some other recovery liquid which 30 is a solvent of the bromid or other separant and which has a boiling point substantially below that of the separant, the washing action being carried on at a temperature below that of the boiling point of the recovery liquid. The solution of the separant and the recovery liquid that has been used to 35 wash off the solids is then subjected to heat to evaporate off the recovery liquid, while the solids, coated with the recovery liquid, 40 are also subjected to heat to drive off the recovery liquid; the recovery liquid being condensed and re-used in the recovery step of the process, while the separant is re-used in the separating step of the process. In 45 the above named application I claim the recovery, from the separated solids, of the liquid bromid, or other separant having a specific gravity between the specific gravities of the solids, by washing the solids in liquid 50 carbon bisulfid, or other solvent of the separant having a boiling point below that of the separant, at a temperature above the melting point of the separant and below the

boiling point of the solvent, and then recovering the separant from the solution by 55 evaporating the solvent.

My present invention is, in one aspect, an improvement upon, and an outgrowth of, the process just described, while in another aspect, it is an independent invention, in 60 that it is applicable to a wider range of liquids than that to which the described process is applicable.

While the bromids above mentioned, by reason of their specific gravities and other 65 qualities, have characteristics closely approximating the ideal requirements of a separating liquid, it is well known that different kinds of ore have different specific gravities, and, therefore, even if, as applied 70 to one kind of ore, the separating liquid has an intermediate specific gravity corresponding closely to what is theoretically required, it may be unavailable, or undesirable, for another kind of ore. It should also be borne 75 in mind that the ideal product which is most suitable for smelting should be composed not of pure iron ore, but of iron ore having a fairly defined proportion of silicious material. With each ore of known 80 characteristics, it is possible to calculate the theoretically required specific gravity of the separant, and it is one of the objects of my invention to provide a process whereby a separant of the specific gravity required for 85 any ore may be provided; while at the same time provision is made for the recovery of the separant from the solids so that it may be saved for re-use.

In carrying out my improved process I 90 prefer to use a bromid as the main constituent of the separating liquid and to employ liquid carbon bisulfid as the recovery solvent; but instead of using, as a separant, the bromid in its pure state, I use it in solution 95 with such a quantity of the carbon bisulfid (which has a substantially lower specific gravity) as will give a separant of the desired specific gravity. The separated solids are then subjected, as heretofore, to the 100 washing action of pure carbon bisulfid in order to remove therefrom the adherent separant, and the washed solids are subjected to the mild heat required to evaporate off the carbon bisulfid, which is condensed and 105 re-used. The solution from the recovery ves-

sel, however, is preferably not heated to the extent required to drive off all the carbon bisulfid, but only that part of the carbon bisulfid is driven off which will leave a solution having the same proportions of heavy salt and recovery liquids as were contained in the original separant; the solution remaining being thus adapted for re-use as a separant. If a larger quantity of the carbon bisulfid is driven off than that mentioned, sufficient carbon bisulfid is afterward added to provide a separant of the desired specific gravity. I, therefore, desire it to be understood that my process contemplates either driving off the exact quantity of carbon bisulfid required to leave a solution having the proportions of heavy salt and carbon bisulfid desired for the separant, or driving off the carbon bisulfid in such quantity as to leave a solution containing less carbon bisulfid than is required to provide a separant of the desired specific gravity.

It will be understood that the practice of this process leaves open a fairly wide range of substances from which to select the solvent recovery liquid and the main constituent of the separant. The latter should be a comparatively heavy salt, while the recovery liquid should be one which does not chemically react or combine with the heavier salt except to form the solution.

Thus, assume that the required specific gravity of the separant is 3.10. We can make such a separant by using a solution of tin bromid in carbon bisulfid, the required percentage of the two constituents being readily calculable. After the solids are separated in this solution, they are then separately subjected to the washing action of pure carbon bisulfid, whereby the separant is removed from the solids. The resultant solution of carbon bisulfid and bromid is of a specific gravity but little greater than that of carbon bisulfid itself, because it is mostly carbon bisulfid with a relatively very small quantity of tin bromid in solution. From this solution, the major portion of the carbon bisulfid is evaporated until the residual liquid in the evaporator contains the same proportion of bromid and carbon bisulfid as the original separant.

Having now fully described my invention, what I claim and desire to protect by Letters Patent is:

1. In the separation of solids of different specific gravities, the process which consists in separating the solids in a solution of two liquids of different specific gravities but each of a specific gravity greater than that of water, washing the separated solids that are thus wet with the separant in a separate quantity of the lighter liquid to eliminate from the solids the heavier constituent of the separant, and then separating from the

solution at least all the solvent in excess of that required to leave a solution having the desired specific gravity of the separant.

2. In the separation of solids of different specific gravities, the process which consists in separating the solids in a solution of two liquids of different specific gravities the lighter of which is of a specific gravity greater than that of water and has a substantially lower boiling point than the heavier, eliminating from the separated solids, thus wet with the separant, the heavier constituent of the separant by washing with a separate quantity of the lighter liquid, and distilling off from the solution at least so much of the lighter liquid as will leave a solution of the two liquids in the proportions required for use as a separant.

3. In the separation of solids of different specific gravities, the process which consists in separating the solids in a liquid separant composed of a solution of a relatively heavy salt in a solvent thereof, said solvent having a specific gravity greater than that of water, then driving off the separant adhering to the separated solids by subjecting them to the washing action of a separate quantity of said solvent, and then separating from the solution of washing liquid and heavy salt the quantity of the solvent required to leave a liquid having the characteristics of the original separant.

4. In the separation of solids of different specific gravities, the process which consists in separating the solids in a liquid separant composed of a solution of a salt in a solvent thereof of a specific gravity greater than that of water but of lower specific gravity, and having a substantially lower boiling point, than the salt, washing the solids that are thus wet with the separant in a separate quantity of the solvent, and then subjecting the solution of washing liquid and separant to heat to the extent required to drive off at least all the solvent in excess of that required to leave a separating solution of the desired specific gravity.

5. In the separation of solids of different specific gravities, the process which consists in separating the solids in a solution of a relatively heavy salt in carbon bisulfid, eliminating from the solids the heavy solution by washing with carbon bisulfid, and distilling off from the resultant solution at least the excess of carbon bisulfid required to provide a separant of the desired specific gravity.

6. In the separation of solids of different specific gravities, the process which consists in separating the solids in a solution of a bromid in carbon bisulfid, recovering the bromid from the solids that are thus wet with the separant by washing the latter with carbon bisulfid and distilling off from

the solution an amount of carbon bisulfid at least equal to that used for washing.

7. In the separation of solids of different specific gravities, the process which consists in separating the solids in one liquid and then washing them in another liquid, both liquids having a specific gravity above that of water, the separating liquid comprising a solution of a relatively heavy salt in the 10 washing liquid.

8. In the separation of solids of different specific gravities, the process which consists in separating the solids in one liquid and then washing them in another liquid, the 15 separating liquid comprising a solution of a relatively heavy salt in the washing liquid and evaporating and condensing the washing liquid and reusing in the washing operation the liquid so evaporated and condensed.

20 9. In the separation of solids of different specific gravities, the process which consists in separating the solids in a solution of two liquids of different specific gravities, washing the separated solids that are thus wet

25 with the separant in a separate quantity of the lighter liquid to eliminate from the solids the heavier constituent of the separant, then separating from the solution at

least all the solvent in excess of that required to leave a solution having the desired 30 specific gravity of the separant and reusing in the washing operation the solvent so separated.

10. In the separation of solids of different specific gravities, the process which consists 35 in separating the solids in a solution of a bromid and carbon bisulfid.

11. In the separation of solids of different specific gravities, the process which consists in separating the solids in a solution of a 40 bromid and carbon bisulfid and then washing the solids in carbon bisulfid.

12. In the separation of solids of different specific gravities, the process which consists in separating the solids in a solution of a 45 relatively heavy salt and carbon bisulfid.

13. In the separation of solids of different specific gravities, the process which consists in separating the solids in a solution of a relatively heavy salt and carbon bisulfid and 50 then washing the solids in carbon bisulfid.

In testimony of which invention, I have hereunto set my hand, at New York, N. Y., on this 30th day of August, 1916.

ADRIAAN NAGELVOORT.
